UNITED STATES PATENT OFFICE.

JAMES G. HEASLET, OF DETROIT, MICHIGAN, ASSIGNOR TO THE GARFORD COMPANY, OF ELYRIA, OHIO, A CORPORATION OF OHIO.

IGNITER-TIMING DEVICE.

No. 922,764.

Specification of Letters Patent.

Patented May 25, 1909.

Application filed July 17, 1907. Serial No. 384,173.

To all whom it may concern:

Be it known that I, JAMES G. HEASLET, a citizen of the United States, and a resident of Detroit, in the county of Wayne and State 5 of Michigan, (whose post-office address is 820 West Warren avenue, Detroit, Michigan,) have invented certain new and useful Improvements in Igniter-Timing Devices, of which the following is a full, clear, and exact 10 description, whereby any one skilled in the art may make and use the same.

The invention relates to an ignition mechanism, and is particularly adapted for use in connection with liquid hydro-carbon and gas 15 engines. It is designed to be actuated directly by a motor or engine which it controls, and has certain features of precision of action hereinafter more fully defined.

The objects of the invention are to provide 20 an ignition device the actuation of which is entirely dependent upon the rotation of the motor shaft.

A further object is to provide compensation for "high" and "low spark" by providing a break of the circuit at a known velocity which is constant whether the engine is running at high or low speed.

A further object is to provide special means for controlling the advance or retardation of the instant of ignition.

Referring to the drawings:—Figure 1 is a plan view of the igniting device showing the igniter plugs, appurtenant parts and their connections. Fig. 2 is a view in elevation 35 with parts shown in Fig. 1, also illustrating the manner of connecting the moving parts to the motor shaft.

It has of course, long been common practice to use both primary and secondary forms 40 of ignition for exploding a charge of gas or vapor in the cylinders of a gas engine; these devices have been controlled in various manners.

The igniter device herein described, 45 tempers the use and coöperation of what is now commonly known as the two-pole low tension magneto which of course is driven directly from the engine shaft, or a suitable timing shaft and supplies the necessary current for the igniter and is entirely dependent 50 for its rotation, upon the rotation of the motor shaft. The igniting device hereinafter described is also positively driven from the

motor shaft, and therefore the entire ignition system depends primarily for its operation, upon the movement of said shaft.

In the drawings there are shown simply the parts of the igniting mechanism which are applied to the cylinders of the gas engine. The magneto is not illustrated, as it is a well-known type of device for producing electric energy. One pole of said magneto is grounded upon the motor, while the other pole is connected through insulated wires and conduits, with the insulated electrodes of the igniter plugs.

Referring to the drawings:—The numerals 1 denote plugs adapted to be inserted in the cylinder heads of a gas engine and bear the several parts of the operating mechanism of the make and break device. They are bodily removable and may be readily inserted in the cylinder heads. They of course may be used on a motor having any number of cylinders and are so interconnected that the controlling mechanism for varying the instant of ignition in one cylinder, will simultaneously vary in like proportion, the timing of the instant of ignition in the several coupled mechanisms. The plugs 1, have a main body part 2 of cylindrical form, surmounted by a cap or flange 3. The body part 2 is of considerable depth and extends through the head and jacket of the cylinder in such manner that the make and break for disrupting the circuit extends into the combustion chamber of the cylinder.

Extending through the plug 1 is an insulated bar or insulated electrode 4 which is connected through an insulated wire 5 and bus bar 6 with one pole of the magneto or to one side of whatever circuit may be used. This insulated electrode 4 projects through the plug and lies in position to be engaged by a movable electrode 7. The latter is secured to the lower end of the shaft 8 which extends through the plug, and is surmounted by an adjustable collar 9. Loosely mounted upon the shaft 8 is a trigger or finger 10 which is connected to the lower end of a coiled spring 11, the upper end of which is connected to the collar 9.

Secured to the shaft 8 is an arm 12, normally pulled to a definite position by a spring 13. This arm and spring normally hold the movable electrodes 7 away from the in

2
 lated plugs or insulated electrodes 4, and it will be noted that the movement of the trigger or finger 10, will move the movable electrode against the insulated electrode through the medium of the spring 11, which is of course of sufficient tension to overcome the pull of the spring 13. This spring arrangement allows the necessary compensation for "high" and "low spark" and insures a positive contact between the movable electrode and insulated electrode at all speeds of the engine. The spring 13, on the other hand, insures a separation of the movable electrode and insulated electrode at a uniform speed no matter what the speed of the engine, thus maintaining the drawing of a spark or arc of uniform quality. It will therefore be seen that no matter what the instant of ignition, the speed of separation of the contacting points will be constant, and will therefore produce a uniform spark irrespective of the speed of the engine.

The trigger 10 and its movable electrode 7 are moved into contacting position with the plug or insulated electrode 4 by a trip lever 14. This lever is mounted upon a bearing eccentrically arranged upon the eccentric disk 16, which is secured to the upper end of a shaft 17, the lower end of which terminates in a gear 18. This gear 18 meshes with gear 19 upon the shaft 20, which of course is directly geared to the engine shaft. The shaft 20 is the time shaft which bears the cams for operating the inlet valves of the engine cylinders. From the above it will be seen that the trip lever 14 is positively driven from the engine shaft and will be rotated at a speed varying with the speed of the engine. The eccentric disks 16 are made adjustable upon their shafts in order that the trip levers 14 may be set to the proper initial position providing a uniform movement for the several cylinders.

Mounted upon the plug 1 is a timing eccentric 21, having an extended lever 22 provided in its outer and under side with a roll 23 which projects into a cam groove 24 shaped in the form of a thread. This thread or cam groove is cut in a cylinder 25 which is secured to and rotates with a shaft 26 suitably supported with reference to the engine cylinders and igniter plugs. The end of the shaft 26 bears a pinion 27 which meshes with a segmental gear 28, secured to the upper end of a shaft 29. The lower end of this shaft, through a lever 30 and suitable connections (not shown), may be rotated by the operator whenever it is desirable to change the instant of ignition for securing variations of speed of the engine.

The trip lever 14 is resiliently held against the timing eccentric 21 by a spring 31 so that its reciprocating movements will not be interfered with, but the position of its engaging end 32 may be varied during its strokes by a

change in the position of the timing eccentric 21. Obviously the movement of the shaft 29 will rotate the screw cam block 25 and swing the timing eccentric 21 through the medium of its lever 22 and roll 23. As shown in the drawing, the timing lever 22 is shown in advanced position, and in this position the trip lever 14 will engage and remain in engagement with the trigger 10 for the shortest time possible with the arrangement of parts illustrated.

To retard the instant of ignition, the cam block 25 is rotated, throwing the timing lever 22 to a greater or less extent and permitting the trip lever 14 to assume a lower position upon the timing eccentric 21. This of course permits a longer engagement of the end 32 of the lever 14 and the trigger 10. This results in holding the movable electrode 7 against its insulated electrode a longer period of time; and of course this difference of time in contact of the parts is permitted by the spring connection 11 between the trigger and movable electrode shaft 8.

It will be noted from the above description, that the speed with which the movable electrode 7 is moved into contact with the insulated electrode or plug 4, depends upon the speed of the engine, but whenever the lever 14 trips or drops the trigger 10, the spring 13 will react, always moving the movable electrode 7 and disrupting the circuit at a constant speed irrespective of the speed of the engine.

The current from one pole of the magneto or source of electrical energy is preferably carried to the bus bar 6 through an insulated wire 33, and in practice it is found convenient to arrange this bus bar over the cylinder heads. The flexible conductors 5 which connect the bus bar with the plugs or insulated electrodes 4 are provided with sleeves 34 which fit tightly over the upper ends of the plugs 4, and may be readily removed to break the circuit for any particular cylinder. But one plug has been described herein, as the operating parts for it are identical, and of course it is understood that any number of plugs may be used for a corresponding number of cylinders, the several plugs being interconnected as illustrated in the couplet shown in the drawing.

Obviously the details might be varied to a considerable extent, without departing from the spirit or intent of the invention, and various forms of positive connection might be utilized in lieu of the specific forms shown herein.

What I claim as my invention and desire to secure by Letters Patent is:

1. In an ignition timing device comprising a stationary and a movable contact with a trigger and trip lever for actuating the movable contact; a timing lever mounted appurtenant to the trip lever, a shaft operatively

arranged with reference thereto and bearing a spiral cam, said timing lever having one end projecting into the spiral of the cam.

2. In an ignition timing device comprising a stationary and a movable contact with a trigger and trip lever for actuating the movable contact; an eccentric timing lever appurtenant to the trip lever and controlling its operation, and a spiral cam rotarily mounted for controlling the position of the timing lever.

3. In an ignition timing device comprising a stationary and a movable contact with a trigger and trip lever for actuating the movable contact; an eccentric timing lever appurtenant to the trip lever and controlling its operation, a spiral cam rotarily mounted for controlling the position of the timing lever, and positive means for rotating the spiral cam.

4. In an ignition timing device comprising a stationary and a movable contact with a trigger and trip lever for actuating the movable contact; a timing lever appurtenant to the trip lever, a shaft operatively arranged with reference to said parts and provided with a spiral groove, said groove engaged by

the timing lever, a pinion secured to said shaft, and a segmental gear meshing therewith and means for rotating said segmental gear.

5. In an ignition timing device comprising a plurality of sparking devices, each comprising a stationary and movable contact member and eccentric timing levers for controlling the operation of the movable contact members; a shaft bearing spiral grooves, one for each timing lever, said levers engaging at one end the spiral grooves of the shaft and means for rotating said shaft.

6. In an ignition timing device comprising a plurality of sparking devices, each comprising a stationary and movable contact member and eccentric timing levers for controlling the operation of the movable contact members; a shaft bearing spiral grooves, one for each timing lever and having their spirals opposed in direction, said levers engaging at one end the spiral grooves of the shaft and means for rotating said shaft.
